FRANK M. BROOKS, OF NEW YORK, N. Y.

HANGER FOR LIGHTING-FIXTURES.

1,115,166.

Specification of Letters Patent. Patented Oct. 27, 1914.

Application filed April 10, 1914. Serial No. 830,877.

To all whom it may concern:

Be it known that I, FRANK M. BROOKS, the borough of Brooklyn, in the county of Kings, city and State of New York, have 5 invented an Improvement in Hangers for Lighting-Fixtures, of which the following is a specification.

My present invention relates to a hanger or hook for suspending the shades, globes or 10 bowls of lighting fixtures, and more particularly to a hanger adapted to support the bowls now commonly employed in fixtures for producing the so-called semi-indirect lighting effects. So far as I am aware, the 15 most common manner of supporting these bowls is by suitably suspending a ring, provided with a flange adapted to receive the rim of the bowl, the flange being fitted with set screws which pass through and turn 20 within the same and are adapted at their ends to engage the outer surface of the rim of the bowl to secure it in place. I am also aware that more recently, in some instances, this suspending ring member has been dispensed 25 with and hangers or hooks employed to support the bowl. So far as I am aware, however, these hangers or hooks are recessed to receive a portion of the rim of the bowl, and are also fitted with set screws adapted to 30 turn in the hangers so as to engage the rim of the bowl to hold the same in position. In both these structures, it is necessary to exercise considerable care in adjusting the set screws to place, inasmuch as, if turned too 35 far, they are liable to crack the bowl, and if not turned far enough, they will not properly support the bowl, and even when properly adjusted to place, hangers of this nature do not provide for any relative movement 40 between the bowl and its support, which relative movement is essential to insure against the bowl becoming easily broken or displaced.

Now the object of my present invention is 45 to overcome these difficulties, and in carrying out the same, I preferably employ a hanger comprising a shank fitted with a hook at one end thereof, adapted to receive the end link of a support chain, a member 50 adapted to engage the outer surface of the rim of the bowl, and a resilient member for yieldingly engaging the inner surface of the bowl in order to provide a relative movement between the same and also to se- 55 curely maintain the contact between the

parts at all times so as to properly support the bowl.

In the drawing, Figure 1 is a side elevation of a hanger made in accordance with my present invention, a portion of a fixture 60 bowl being shown in cross section. Fig. 2 is a front elevation of the same. Fig. 3 is a view similar to Fig. 1, showing a modified form of the invention, and Fig. 4 is a front elevation of the resilient member employed 65 in the form of the invention illustrated in Fig. 3.

Referring to the drawing, and particularly to Figs. 1 and 2, my improved fixture 70 preferably comprises a shank body member 10, provided at one end with a hook 11, which, when in use, is the upper end, and, as will be understood, the hook 11 is adapted to receive the end link of the chain 12, by which the hanger and the bowl, connected thereto, are supported. In suitable positions, the shank member 10 is provided with oppositely disposed lugs 13. These lugs are preferably adjacent the end of the hanger opposite the hook 11, and adjacent 75 the hook end of the hanger and on the same side as the lugs 13 the hanger is provided with a boss 14.

Together with the parts hereinbefore described, I employ a resilient member 15, 85 made of sheet metal or other material having a required resiliency and provided adjacent to one end with ears 16 preferably turned at right angles thereto. At this end, the resilient member is provided with an 90 opening through which a screw 17 is passed and turned down into a tapped opening provided therefor in the boss 14, so that when in position the ears 16 extend over the opposite sides of the boss 14 to maintain the 95 resilient member in position on the hanger and permit the other or lower end of the resilient member to extend adjacent to and beyond the lugs 13.

18 designates a bowl adapted for use in a 100 fixture for producing a semi-indirect lighting effect. As is customary, the rim of these bowls is preferably curved, and as illustrated in Figs. 1 and 2, the hereinbefore described hook is placed in position on the rim 105 of the bowl with the lugs 13 bearing against the outer surface thereof and the resilient member 15 bearing against the inner surface thereof, the member 15 providing sufficient resiliency to permit of a relative movement 110

between the hanger and the bowl so as to overcome the liability of cracking the bowl in adjusting the hanger to position, and to also insure the proper contact between the parts of the bowl and the members of the hanger to maintain the same in position at all times.

Referring to Figs. 3 and 4, it will be seen that the resilient member 19 may be curved or provided with a loop 20, between its point of attachment to the hanger and its point of contact with the bowl. In this structure, the resilient member 19 is provided with an additional screw hole or opening 21, through which the screw 22 may be passed to maintain the resilient member in position on the boss of the hanger, with the ears 23 thereof extending over opposite sides of the boss, for the same purpose as hereinbefore described in connection with the preferred form of the invention, as shown in Figs. 1 and 2. It will be further noted that the hanger is so constructed that the end opposite the hook 11, that is to say, opposite the lower end, when in position for use, as indicated at 24, also provides for a contact with the outer surface of the bowl.

I claim as my invention:

1. A hanger comprising a shank, means at one end thereof by which the same may be suspended, lugs adjacent the other end thereof, and a resilient member connected thereto and between which and the said lugs a device to be supported may be received and yieldingly held in position.

2. A hanger for the bowls of lighting fixtures, comprising a shank, a hook at one end thereof by which the same may be suspended, lugs adjacent the other end thereof, and a resilient member between which and the said lugs the rim of the bowl of the lighting fixture may be received and yieldingly secured in position.

3. A hanger for the bowl of lighting fixtures, comprising a shank, a hook at one end thereof and by which the same may be suspended, lugs adjacent the opposite end

thereof adapted to engage the outer surface of the rim of a bowl, and a resilient member adapted to engage the inner surface of the rim of the bowl to yieldingly maintain the same in position in the hanger.

4. A hanger for the bowl of lighting fixtures, comprising a shank, a hook at one end thereof and by which the same may be suspended, lugs adjacent the opposite end thereof adapted to engage the outer surface of the rim of a bowl, a resilient member adapted to contact with the inner surface of the rim of a bowl, and means for securing the said resilient member in position on the said hanger.

5. A hanger for bowls of lighting fixtures, comprising a shank, a hook at one end thereof by which the same may be suspended, lugs adjacent the opposite end thereof, adapted to contact with the outer surface of the rim of a bowl, a boss adjacent the hook end of the hanger, a resilient member, and means for securing the same to the said boss so that it will engage the inner surface of the rim of the bowl to yieldingly maintain the same in position in the hanger.

6. A hanger for bowls of lighting fixtures, comprising a shank, a hook at one end thereof by which the same may be suspended, lugs adjacent the opposite end thereof, adapted to contact with the outer surface of the rim of a bowl, a boss adjacent the hook end of the hanger, a resilient member of sheet metal, ears turned at right angles thereto to engage the opposite sides of the said boss, and a screw passing through the said resilient member and into the said boss in order to maintain the resilient member in position thereon so that it may yieldingly engage the inner surface of the rim of the bowl to secure the hanger in place on the rim of the bowl.

Signed by me this 7th day of April, 1914. 90
FRANK M. BROOKS.
